COLLAPSIBLE CELLULAR CARTON

William H. Inman, Newark, N. Y., assignor to Bloomer Bros. Company, Newark, N. Y., a corporation of New York

Application January 5, 1953, Serial No. 329,623

5 Claims. (Cl. 229—29)

This invention relates to cellular cartons of the variety made from cardboard or other suitable sheet material, for containing eggs or other fragile articles, one object of the invention being to provide an improved carton of the above character having a more simple, practical and efficient construction affording a high degree of strength and resistance to crushing, particularly under vertical pressure on the carton or the contents thereof. Another object is to provide a carton having the above advantages which is capable of being readily cut from sheet material, scored for folding, folded and glued in collapsed condition, and of being easily swung to erected condition by automatic machines of known construction. A further object is to provide a carton of the above character having a form of construction which eliminates externally projecting supporting legs or other irregular projections and presents smooth outer wall surfaces when in erected condition so as to obviate entanglement with one another and to facilitate the stacking of quantities of the filled cartons.

Still a further object is to provide a carton having the above advantages which require a minimum amount of material in proportion to its strength and which is capable of being readily and economically manufactured. To these and other ends the invention resides in certain improvements and combinations of parts, all as will be hereinafter more fully described, the novel features being pointed out in the claims at the end of the specification.

In the drawings:

Fig. 1 is a plan view of a blank of sheet material cut, scored and glued, in accordance with my invention, preparatory to folding;

Fig. 2 is an enlarged fragmentary plan view of the top wall of the carton;

Fig. 3 is an end elevation showing the completed carton in collapsed condition;

Fig. 4 is an end elevation showing the completed carton in the process of erection;

Fig. 5 is an end elevation of the erected carton, and

Fig. 6 is a perspective view showing the carton in erected condition.

This invention is an improvement on the general type of carton disclosed in my prior Patent No. 2,556,088, for the purpose of producing a stronger and more practical, economical and convenient carton.

The embodiment of the present invention, herein disclosed by way of illustration, preferably comprises a one-piece blank, shown generally at 21, of cardboard or other suitable sheet material, cut, scored and glued for folding, as shown in Fig. 1. The blank is shown in Fig. 1 with the outer surfaces of the carton uppermost in order to more clearly show the various cut and score lines which form the parts of the carton, hereinafter described. The blank is of generally rectangular shape, adapted to be economically cut from stock material, and comprises in order, as shown in Fig. 1, a locking flap 23, cover 25, rear wall 27, inner bottom wall plies 29 and 31, outer

2

bottom wall 33, longitudinal partition members or sections 35 and 37, outer bottom wall 39, inner bottom plies 41 and 43, a front wall 45, a top wall 47, and an attaching strip 49.

5 The above sections of the blank are separated by score lines extending across the blank, as shown by multiple lining in the drawings, to facilitate folding, as well understood in the art. The top wall 47 is cut and scored for the downfolding of a series of cross or transverse partitions having three different configurations, as shown at 51, 53 and 55 (Fig. 2), for separating the carton longitudinally into cells.

Thus, the blank is cut through along lines 57 and scored along the lines 59 to permit the downfolding of the cross partitions, as shown in Fig. 6, for coaction with a central longitudinal partition, hereinafter described, to divide the carton into a dozen article-receiving cells. The top wall has a series of short transversely-extending score lines 61 (Fig. 2), located adjacent opposite sides thereof, which in conjunction with score lines 59 form a series of substantially triangular hinge portions 63 about which the transverse partitions may be swung to their downfolded positions, as shown in Fig. 6. Score lines 59 and 61 preferably have short cuts or slits 65 formed therein for decreasing the resistance to the folding of the carton parts along said score lines. The top wall is also formed with a series of cut-outs as at 67 (Fig. 2).

The lower edges of the transverse partitions are preferably notched or slotted centrally, as at 69 (Fig. 2) for engagement with the longitudinal partition, hereinafter described. Transverse partitions 55 are each preferably provided with a pair of short cuts or slits 71 (Fig. 2) which, in conjunction with the central slit 69, form a pair of tab portions adapted to yield slightly as partitions

35 55 are swung into engagement with the longitudinal partition to assist in the frictional engagement therebetween, as disclosed in my prior Patents Nos. 2,277,327 and 2,556,088. Each cross partition is centrally scored longitudinally of the carton, as at 73 (Fig. 2), in addition to slits 69, to facilitate the central folding of the transverse partitions and the top wall in the collapsed condition of the carton, as hereinafter more fully described. The partitions are preferably so arranged that, when the blank is turned over and folded, the three partitions adjacent the right end of the blank, as shown in Fig. 1, fold

40 45 downwardly in a clockwise direction to their erected positions shown in Fig. 6, while the remaining four partitions are arranged to swing in a counterclockwise direction to their erected positions shown in Fig. 6. The longitudinal partition members 35 and 37 are formed with a series of cut-out portions or notches, as at 75 (Fig. 1) to provide, when erected, a series of notches in the upper portion of the longitudinal partition. Notches 75 are open at the upper ends thereof and are arranged to receive the transverse partitions

50 55 which swing down and engage the longitudinal partition in the slits 69 thereof. Partition members 35 and 37 are separated by an interrupted score or fold line 77 (Fig. 1) extending longitudinally of the carton, to assist in reversely folding the partition sections to their juxtaposed position shown in Figs. 4 and 5. Members 35 and

9055 9060 9065 9070 9075 9080 9085 9090 9095 9100 9105 9110 9115 9120 9125 9130 9135 9140 9145 9150 9155 9160 9165 9170 9175 9180

Inner bottom section 85 comprises a lower ply 41 which is separated from outer bottom wall 39 by a score line 93, and an upper ply 43 which is separated from lower ply 41 by a score line 95 and from front wall 45 by a score line 97, as shown in Fig. 1. Inner bottom plies 29 and 31 are preferably provided with a band or strip of glue or other suitable adhesive, as at 99 (Fig. 1), for securing the same together when reversely folded about score line 89 for forming inner bottom section 83. Inner bottom plies 41 and 43 are preferably provided with a band or strip of glue or other suitable adhesive, as at 101 (Fig. 1), for securing the same together when reversely folded about score line 95 for forming inner cushioning bottom section 85. Longitudinal partition sections 35 and 37 are preferably provided with glue or other suitable adhesive, as at 103, on the upper surfaces thereof, as viewed in Fig. 1, for securing the same together when reversely folded along fold line 77 for forming a double-thickness longitudinal partition and bringing bottom walls 33 and 39 into proximity with each other adjacent the inner edges thereof, as shown in Figs. 4 and 5.

Top wall 47 is separated from front wall 45 and attaching strip 49 by irregular, longitudinal-extending fold lines formed in part by the respective series of spaced cuts 57 and in part by the respective series of spaced score lines 59. Cover 25 is separated from rear wall 27 by a score line 105 (Fig. 1) and from locking strip 23 by a score line 107 (Fig. 1).

The folding and gluing of the carton is preferably done as follows: The blank is passed through a gluing machine which applies glue or other suitable adhesive, as at 99, 101, 103 and along the upper surface, as viewed in Fig. 1, of attaching strip 49, as at 109. The blank is preferably broken along score lines 81 and 79 and then plies 29 and 31, and 41 and 43 are reversely folded along score lines 89 and 95, respectively, for forming the double-thickness inner bottom sections 83 and 85. The blank is then reversely folded along score line 79 bringing sections 35 and 37 into juxtaposed relationship for forming the double-thickness, longitudinal partition. Thereafter, front wall 45 and top wall 47 are swung as a unit about score line 97 upwardly over the top of the longitudinal partition. Top wall 47 is then reversely folded along score line 73. Inner bottom section 83 is moved inwardly toward the longitudinal partition and passes between the underside of attaching strip 49 and the longitudinal partition. The parts are then swung to collapsed position and cover 25 and rear wall 27 folded upwardly along score line 105 to their positions shown in Fig. 3, bringing rear wall 27 into contact with attaching strip 49 to which it is securely held by adhesive 109.

When the folding operation has been completed, the carton is in collapsed condition, as shown in Fig. 3, and requires a minimum of space for storage or shipment. The upper portion of the longitudinal partition extends upwardly through slits 69 in the corresponding transverse partitions so that once the carton is glued and folded, the parts will always remain in proper alignment and the carton may thereafter be quickly and easily erected without special operations or machines to hold the parts in position. That is, in erecting the carton, the transverse partitions are forced downwardly into notches 75 in the longitudinal partition while said longitudinal partition is forced downwardly to move outer bottom walls 33 and 39 into nearly coplanar relationship and spread the front and rear walls, as shown in Fig. 4. At this point the transverse partitions are substantially horizontal and well below the top of the longitudinal partition, and may be readily swung to their substantially vertical, erected positions by hand, or by known erecting devices, thereby completing the erection of the carton. Partitions 51 and 53 are preferably shaped so that the outer edges thereof engage the upper surfaces of bottom plies 29 and 43 for holding inner bottom sections 83 and 85, respectively, in their inclined positions shown in Fig.

5, and for increasing the frictional interengagement of the carton parts in their erected condition thereof.

After filling, cover 25 is folded along score line 105 and locking flap 23 folded along score line 107 into depending position relative to cover 25. Flap 23 is provided with a series of locking hooks 111 and a tab 113 (Fig. 1) which are moved downwardly into engagement with and between hinge portions 63, for securing the cover in closed position, as well understood in the art.

Transverse partitions 51 are preferably provided on opposite sides thereof with small projecting lugs 115 (Fig. 2) which are adapted to engage the inner surfaces of the front and rear walls of the carton when the partitions are swung to erected position, as shown in Fig. 5, thereby increasing the frictional engagement between the partitions and the side walls of the carton. Partitions 53 have similar lugs or projections 117 formed therein and are provided with a pair of short slits or cuts 119 (Fig. 2) which increase the flexibility of said lugs and allow the same to bend out of alignment with the main portion of partitions 53 so as to provide an enlarged area of frictional engagement between the partitions and the front and rear walls of the carton. Partitions 55 are each provided with slits 71 which, in conjunction with central slit 69, form a pair of substantially triangular tab portions which are adapted to bend and frictionally engage the longitudinal partition as partitions 55 are swung into erected position. In addition, partitions 51 are preferably provided with a series of interrupted cut or slit lines 121 arranged as shown in Figs. 1 and 2 for allowing partitions 51 to bow outwardly towards the adjacent end of the carton between the front wall and the longitudinal partition, and between the longitudinal partition and the rear wall, thereby increasing the length of the end cells of the carton.

The longitudinal partition is preferably of such a height as to engage and support the center of cover 25 when the cover is swung to its closed position, as shown in broken lines in Fig. 5. This allows vertical loads on the cover to be transmitted directly to the outer bottom of the carton by the longitudinal partition without affecting the contents of the carton. The inner cushioning bottom sections are secured only at their outer edges, as shown in Fig. 4, and upon erection of the carton swing downwardly until they engage opposite sides of the longitudinal partition as shown in Fig. 5. In this position bottom sections 83 and 85 are free to bow or flex downwardly, or move upwardly, under impact and thereby provide a resilient cradling of the eggs, or other contents of the carton. In addition, inner bottom sections 83 and 85, outer bottom walls 33 and 39, and the lower portion of the longitudinal partition form a truss-like construction of substantially triangular shape, comprising in effect two smaller truss-like triangles, which impart considerable strength to the upper portions of the longitudinal partition, the transverse partitions, and through the longitudinal partition, to the cover of the carton. This construction results in a much stronger carton of the type which may be conveniently stacked one upon another without fear of crushing the contents and which are capable of resisting heavy shocks or impacts. In addition, as there are no feet or other projections depending below outer bottom walls 33 and 39, the outer surfaces of the carton are smooth and are not likely to engage or entangle one another.

Thus, it will be seen that my invention provides an improved carton having a smooth outer bottom and an inclined inner cushioning bottom which supports and cradles the contents. The inner bottom sections are so spaced from the outer bottom walls that impacts will be absorbed by the carton or transmitted through the carton without injury to the contents thereof. The cover of the carton is not only supported along the rear edge thereof by rear wall 27, and along the front edge thereof by the front wall 45 and closure flap 23, but it is also supported midway between the front and rear edges thereof by the upper edge of the longitudinal partition. My improved carton

has the further advantages that the above construction is accomplished with a minimum of material, and the carton is of such a type that it may be readily and economically manufactured and folded to collapsed condition for shipment or storage. Thereafter, the carton may be readily erected by hand or by mechanical erecting devices to its condition shown in Figs. 5 and 6, since the top wall and longitudinal partition are continuously engaged and guided in movement upon each other.

It will thus be seen that the invention accomplishes its objects and, while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A cellular carton comprising a blank of sheet material cut, scored and folded to form front and rear side walls, a pair of inner cushioning bottom sections having upper plies hingedly connected to said side walls along the lower edges thereof and extending upwardly and inwardly into proximity with each other, said inner bottom sections having lower plies hingedly connected to the respective upper plies along the inner edges thereof and extending downwardly and outwardly adjacent the bottoms of said side walls, respectively, a pair of outer bottom walls hingedly connected to said lower plies along the outer edges thereof and extending inwardly into proximity with each other, upwardly extending longitudinal partition members hingedly connected to said outer bottom walls adjacent the inner edges thereof for forming a central longitudinal partition extending upwardly between said inner cushioning bottom sections, said partition members being hingedly connected to each other along the upper edges thereof, and a top wall hinged to and connected with said front and rear walls and having therein a series of transverse partitions hingedly connected thereto and folded downwardly therefrom between said side walls and on opposite sides of said longitudinal partition to provide a plurality of separate article-receiving cells on each side of said longitudinal partition.

2. A cellular carton comprising a blank of sheet material cut, scored and folded to form front and rear side walls, a cover hinged to said rear wall, a pair of inner cushioning bottom sections having upper plies hingedly connected to said side walls along the lower edges thereof and extending upwardly and inwardly into proximity with each other, said inner bottom sections having lower plies hingedly connected to the respective upper plies along the inner edges thereof and extending downwardly and outwardly adjacent the bottoms of said side walls, respectively, a pair of outer bottom walls hingedly connected to said lower plies along the outer edges thereof and extending inwardly into proximity with each other, upwardly extending longitudinal partition members hingedly connected to said outer bottom walls adjacent the inner edges thereof for forming a double thickness central longitudinal partition extending upwardly between said inner cushioning bottom sections, said partition members having their upper edges hingedly connected together and located in supporting proximity to said cover, and a top wall hinged to and connected with said front and rear walls and having therein a series of transverse partitions hingedly connected thereto and folded downwardly therefrom between said side walls and on opposite sides of said longitudinal partition to provide a plurality of separate article-receiving cells on each side of said longitudinal partition.

3. A cellular carton comprising a blank of sheet material cut, scored and folded to form front and rear side walls, a pair of inner cushioning bottom sections having upper plies hingedly connected to said side walls along the lower edges thereof and extending upwardly and in-

wardly into proximity with each other, said inner bottom sections having lower plies hingedly connected to the respective upper plies along the inner edges thereof and extending downwardly and outwardly adjacent the bottoms of said side walls, respectively, a pair of outer bottom walls hingedly connected to said lower plies along the outer edges thereof and extending inwardly into proximity with each other, upwardly extending longitudinal partition members hingedly connected to said outer bottom walls adjacent the inner edges thereof for forming a double thickness central longitudinal partition extending upwardly between said inner cushioning bottom sections, said partition members being hingedly connected to each other along the upper edges thereof, and a top wall hinged to said front wall adjacent the upper edge thereof and being foldably connected with said rear wall, said top wall having therein a series of transverse partitions hingedly connected thereto and folded downwardly therefrom between said side walls and on opposite sides of said longitudinal partition to provide a plurality of separate article-receiving cells on each side of said longitudinal partition while said outer bottom walls are foldable downwardly about the hinge connections between said outer bottom walls and the respective longitudinal partition members for collapsing said carton to substantially flat condition.

4. A cellular carton comprising a blank of sheet material cut, scored and folded to form front and rear side walls, a pair of inner cushioning bottom sections having upper plies hingedly connected to said side walls along the lower edges thereof and extending upwardly and inwardly into proximity with each other adjacent the center of the carton, said inner bottom sections having lower plies hingedly connected to the respective upper plies along the inner edges thereof and extending downwardly and outwardly adjacent the bottoms of said side walls, respectively, a pair of outer bottom walls hingedly connected to said lower plies along the outer edges thereof and extending inwardly into proximity with each other, upwardly extending longitudinal partition members hingedly connected to said outer bottom walls adjacent the inner edges thereof for forming a double thickness central longitudinal partition extending upwardly between said inner cushioning bottom sections, said partition members being hingedly connected to each other along the upper edges thereof, and a top wall hinged to and connected with said front and rear walls and having therein a series of transverse partitions hingedly connected thereto and folded downwardly therefrom between said side walls and on opposite sides of said longitudinal partition to provide a plurality of separate article-receiving cells on each side of said longitudinal partition, said inner cushioning bottom sections being wider than the outer bottom walls and engaging opposite sides of said longitudinal partition at points spaced above the juncture between said outer bottom walls and said longitudinal partition for holding said inner cushioning sections in upwardly-inclined position and in spaced relationship with said outer bottom walls along the inner edges thereof; said inner cushioning sections, outer bottom walls and longitudinal partition forming a relatively rigid, truss-like support of substantially triangular shape for firmly supporting said inner cushioning sections and longitudinal partition, with a smooth outer bottom surface for said carton.

5. A cellular carton comprising a blank of sheet material cut, scored and folded to form front and rear side walls, a cover hinged to said rear wall, a pair of inner cushioning bottom sections having upper plies hingedly connected to said side walls along the lower edges thereof and extending upwardly and inwardly into proximity with each other, said inner bottom sections having lower plies hingedly connected to the respective upper plies along the

inner edges thereof and extending downwardly and outwardly adjacent the bottoms of said side walls, respectively, a pair of outer bottom walls hingedly connected to said lower plies along the outer edges thereof and extending inwardly into proximity with each other, upwardly extending longitudinal partition members hingedly connected to said outer bottom walls adjacent the inner edges thereof for forming a double thickness central longitudinal partition extending upwardly between said inner cushioning bottom sections, said partition members having their upper edges hingedly connected together and located in supporting proximity to said cover, and a top wall hinged to and connected with said front and rear walls and having therein a series of transverse partitions hingedly connected thereto and folded downwardly therefrom between said side walls and on opposite sides of said longitudinal partition to provide a plurality of separate article-receiving cells on each side of said longitudinal partition, said inner cushioning bottom sections being wider than
